UNITED STATES PATENT OFFICE.

JOHN J. TYER, OF GREENSBORO, NORTH CAROLINA.

METHOD FOR MAKING BOXES.

Application filed February 24, 1923. Serial No. 621,025.

To all whom it may concern:

Be it known that I, JOHN J. TYER, a citizen of the United States, residing at Greensboro, in the county of Guilford and State 5 of North Carolina, have invented certain new and useful Improvements in Methods for Making Boxes, of which the following is a specification, reference being had to the accompanying drawings.

10 This invention relates to improvements in methods for making boxes and particularly a shouldered box and an associated cover and it is an object of the invention to provide a novel and improved method of this 15 general character wherein the box may be formed of two or more parts so cut as to be shaped and formed around a core and wherein said parts are effectively maintained in assembled relation by the use of one piece 20 of trimming paper and applied by one gluing operation, said assembled parts being cut as desired and in a manner to form the box bottom part and the box cover part, the core being removed after the required incision or cut has been made.

25 The novel features of my invention will hereinafter be definitely claimed.

In order that my invention may be the better understood, I will now proceed to describe the same with reference to the accompanying drawings, wherein:—

Figure 1 is a view in perspective illustrating the initial step in my improved method;

Figure 2 is a view in perspective illustrating a second step;

Figure 3 is a view in perspective with portions broken away illustrating additional steps;

Figure 4 is a view in perspective with a 40 portion broken away illustrating a manner of cutting;

Figure 5 is a sectional view taken through the assembly as illustrated in Figure 4;

Figure 6 is a view in perspective illustrating a further embodiment of my invention;

In my method I employ a core C of requisite size dimensions and which may be made of wood, metal or any desired material and which is provided therethrough with the 50 openings 1 in which the digits of a hand are adapted to be inserted to remove the core after the box has been completed. A marginal portion of the core C is defined by the outstanding flanges 2 of a width substantially equal to the thickness of the inner or first side strip 3. The flanges 2 also pro-

vide a surface equal to the larger face of the box structure preferably the top.

As herein disclosed the core C is placed upon a suitable support with the flange 2 60 lowermost and a sheet or box bottom part 4 of cardboard cut to proper size and configuration is superimposed upon the core as illustrated in Figure 1. The strip 3 is then applied around the sides of the core C, said 65 strip 3 constituting the box shoulder strip. The outer or second side strip 5 is then applied around the strip 3, said strip 5 constituting the box wall strip. A sheet or box top part 6 of cardboard is applied upon the 70 face of the core C defined by the flanges 2.

After the foregoing assembly of the box parts the strip 7 of box trimming paper or the binding paper part is applied around the strip or part 5. This strip or part 7 has adhesive applied to a face thereof whereby the strip may be effectively and conveniently applied. The strip 7 is also of a width materially in excess of the width of the strip or part 5 so that the marginal portions of the 80 strip 7 may be caused to overlap and be adhesively secured to the marginal portions of the sheets or parts 4 and 6 and also to the edges of the strips or parts 3 and 5 whereby the various parts of the box are effectively 85 maintained in assembled relation. It is to be particularly noted that the parts of the box are maintained in such assembled relation by a single adhesive or gluing operation.

After the parts of the box have been properly assembled an incision is made at a desired position through the strip 7 and the outer strip or part 5 whereby the lid and box are separated from each other and with the 90 box provided with the shoulder for requisite coaction with the lid. The incision 8 may be produced at any point between the longitudinal margins of the outer strip or part 5 in order to produce a box with a full shoulder or with a shoulder only reaching a part of the way up toward the top. The location and character of the incision does not however form any particular part of my invention.

In Figure 6 I illustrate a modified form of my invention wherein the sheet or box bottom part 4' has the box shoulder strip part comprised in the flaps 3' particularly formed with the box bottom part or sheet 4' 110 while the flaps 5' are comprised in the box wall strip part and are integrally formed with

the box top part or sheet. In Figure 6 an adhesive strip is applied to this form of box and the requisite incision made through said strip and the flaps 5' in the same manner and for the purpose as hereinbefore set forth with respect to the first embodiment of my invention. This embodiment illustrated in Figure 6 is for the purpose to clearly show that the box proper may be built in various ways.

From the foregoing description it is thought to be obvious that my improved method is particularly adapted for use by reason of the convenience and facility with which it may be employed and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A method of making a shouldered box and lid therefor consisting in forming a closed hollow member from a plurality of separable parts, applying a single adhesive strip around the sides of the hollow member and engaged with the top and bottom thereof to hold the parts assembled, and making an incision through the binding strip and certain of the parts to separate the hollow member into a shouldered box and lid.
2. A method of making a box consisting in forming around a core a closed hollow member of a plurality of parts, applying a single adhesive strip around the sides of the hollow member and engaged with the top and

bottom thereof for holding the parts assembled and then cutting an incision through the binding strip and certain of the parts to separate the hollow member into a shouldered box and lid.

3. A method of producing a shouldered box and lid consisting in building a hollow closed member of a plurality of parts providing side walls of separable parts, applying a single adhesive strip around the sides of the member for holding the parts of the member in assembled relation and then cutting through the adhesive strip and the outer parts of the side walls to divide the member into a shouldered box and lid.

4. A method of producing a shouldered box and lid consisting in building around a core a hollow closed member of a plurality of parts providing side walls of separable parts, applying a single adhesive strip around the sides of the member for holding the parts of the member in assembled relation and then cutting through the adhesive strip and the outer parts of the side walls to divide the member into a shouldered box and lid.

5. A method of making a shouldered box and lid therefor consisting in forming a closed hollow member from a plurality of separable parts, applying a single adhesive strip around the sides of the hollow member and engaged with each of the parts of said member to hold the parts assembled, and making an incision through the binding strip and certain of the parts to separate the hollow member into a shouldered box and lid.

In testimony whereof I hereunto affix my signature.

JOHN J. TYER.
